UNITED STATES PATENT OFFICE.

GEORGES JEANTET, OF BILBAO, SPAIN.

EXPLOSION-MOTOR.

1,386,572.

Specification of Letters Patent.

Patented Aug. 2, 1921.

Application filed July 11, 1917. Serial No. 179,978.

To all whom it may concern:

Be it known that I, GEORGES JEANTET, a citizen of the French Republic, residing at Bilbao, in the Province of Vizcaya and 5 Kingdom Spain, have invented certain new and useful Improvements in Explosion-Motors, of which the following is a specification.

My invention relates to improvements in 10 internal combustion engines.

An important object of the invention is to provide a novel form of pitman connection between the piston and the crank-shaft of the engine, so that a simplified piston may 15 be employed having the ends thereof operating in the explosion and compression chambers.

Other objects and advantages of the invention will be apparent during the course 20 of the following description.

In the accompanying drawings forming a part of this specification and in which like numerals are employed to designate like parts throughout the same,

25 Figure 1 is a side elevation of an engine embodying my invention, and

Fig. 2 is a transverse sectional view 30 through the cylinder taken at a right angle to Fig. 1.

In the drawings, wherein for the purpose of illustration is shown a preferred embodiment of my invention, the numeral 5 designates a crank case, provided upon its opposite sides with openings 6, which lead into 35 casings 7, rigidly attached to the crank case as shown.

The casings 7 are arranged near the lower end or bottom of the crank case 5, and receive ball-bearings 8, having the ends 9 of 40 a crank shaft 10 journaled therein, as shown. This crank shaft embodies cranks 11, connected by pins 12.

The numeral 13 designates a pair of cylinders, of substantial length. These cylinders project downwardly into the crank case 5, and extend vertically therein. The cylinders 13 are preferably cast integral 45 with a horizontal plate 14, disposed upon the top of the crank case, and bolted or otherwise rigidly secured thereto, as shown at 15.

The upper end of each cylinder 13 is surrounded by a water jacket 16, receiving water through an inlet 17, and discharging 50 the same through an outlet 18. The func-

tion of the water jacket is to retain the upper end of the cylinder 13 suitably cool.

The upper end 19 of the cylinder 13 functions as an explosion chamber, while the lower end 20 thereof serves as a compression 60 chamber. A tubular member 21 is connected with the explosion chamber 19, and is adapted for the reception of a spark. The lower end of the compression chamber 20 is internally screw threaded to receive a portion of 65 an externally screw threaded cap 23, whereby to vary the volume of the compression space at will.

Each compression chamber 20 is provided upon its side with a fuel inlet or opening 24, 70 and a conduit 25 to supply the fuel or gas thereto. The compression chamber 20 is further provided, at or near its lower end with an outlet opening 26, leading into a passage or port 27, discharging into the 75 lower end of the explosion chamber 19, through an opening 28. Disposed opposite the opening 28 is an exhaust conduit 29, leading into the lower end of the explosion chamber 19, and in horizontal alinement 80 with the opening 28, as shown.

Mounted to reciprocate within the cylinder 13 is a cylindrical piston 30, having a slightly smaller diameter, with its ends operating within the chambers 19 and 20. At 85 its ends, the double ended piston 30 has rings 31, extending radially beyond the same and of substantially the diameter of the bore of the cylinder 13, to fit snugly therein. It is thus apparent that these rings 90 or flanges slidably contact with the interior of the cylinder 13 while the piston 30 is spaced therefrom.

The piston 30 is provided at a point equidistantly spaced from the ends thereof with 95 an annular groove 32, and a transverse opening 33. The transverse opening 33 receives a transverse pin 34, operating through elongated slots 35 formed in the intermediate portions of the cylinder 13. Pivotally connected with the ends of the transverse pin 34 are pitmen 36, arranged exteriorly of the cylinder 13 and within the crank case 5. At their lower ends, the pitmen are preferably formed integral with a sleeve element 37, 100 rigidly connected with a coaxing sleeve element 38, by bolts 39. These sleeve elements pivotally receive the shaft 12. The pitmen 36 and sleeve 37 form a U-shaped member, 105 as shown.

The operation of the apparatus is as follows:—

When each piston 30 descends, upon the explosion of the charge in the chamber 19, 5 the same uncovers the exhaust port 29 and inlet port 28. The products of combustion are thereby exhausted to the atmosphere and the fresh charge fed into the chamber 19 through the opening 28. The charge is compressed within the chamber 20, upon the 10 down stroke of the piston, and drawn into the same upon the upstroke. Particular attention is called to the fact that the pitmen 36 operate exteriorly of the cylinder 13, and 15 interiorly of the crank case.

It is to be understood that the form of my invention herewith shown and described is to be taken as a preferred embodiment of the same and that various changes in the 20 shape, size, and arrangement of parts may be resorted to without departing from the spirit of my invention or the scope of the subjoined claims.

Having thus described my invention, what 25 I claim is:—

1. An internal combustion engine having a crank case, a piston-cylinder secured thereto and projecting within and beyond such crank case, a conduit formed length- 30 wise the cylinder within the crank case, the lower end of the cylinder within the crank case having a fuel inlet port and also a fuel outlet port leading to said conduit, the upper portion of the cylinder beyond the crank 35 case having a fuel inlet port leading from said conduit and also an exhaust outlet port, a piston movable in the cylinder and forming the sole controlling means for all of said ports, and crank means connected to 40 said piston and operating beyond the cylinder and wholly within the crank case.

2. An internal combustion engine having a crank case, a plate closing the upper end of the crank case, a piston-cylinder secured thereto and projecting within and beyond such crank case, a conduit formed length- 45 wise the cylinder within the crank case, the lower end of the cylinder within the crank case having a fuel inlet port and also a fuel outlet port leading to said conduit, the upper portion of the cylinder beyond the crank 50 case having a fuel inlet port leading from said conduit and also an exhaust outlet port, a piston movable in the cylinder and forming the sole controlling means for all of said 55 ports, and crank means connected to said piston and operating beyond the cylinder and wholly within the crank case.

3. An internal combustion engine having a crank case, a piston-cylinder secured 60 thereto and projecting within and beyond such crank case, a conduit formed length- wise the cylinder within the crank case, the lower end of the cylinder within the crank case having a fuel inlet port and also a fuel 65 outlet port leading to said conduit, the upper portion of the cylinder beyond the crank case having a fuel inlet port leading from said conduit and also an exhaust outlet port, a piston movable in the cylinder and forming the sole controlling means for all of said 70 ports, and crank means connected to said piston and operating beyond the cylinder and wholly within the crank case, and means carried by the cylinder and adjustable relative thereto to vary the volumetric area of 75 said cylinder below the piston.

In testimony whereof I affix my signature.
GEORGES JEANTET.
